United States Patent Office

Des. 199,697
Patented Dec. 1, 1964

199,697

INVERTED MICROSCOPE

Kenneth D. Maier, Mendon, N.Y., assignor to Bausch & Lomb Incorporated, Rochester, N.Y., a corporation of New York

Filed May 24, 1963, Ser. No. 75,038

Term of patent 14 years

(Cl. D57—1)

FIG. 1 is a front perspective view of an inverted microscope showing my new design; and

FIG. 2 is a rear perspective view thereof.

I claim:

The ornamental design for an inverted microscope, substantially as shown and described.
